ROBERT O. OLANDER, OF CALUMET, MICHIGAN

FLUID OPERATED TOOL

Application filed April 24, 1928. Serial No. 272,542.

In fluid operated tools of the pneumatic hammer type and particularly those in which a reciprocating hammer piston has an elongated hammer extension, serious difficulty is experienced because of the tendency of the hammer extension to become scored. This scoring action in turn weakens the extension and is apt to cause it to crack and break. Careful experiment leads to the belief that this may be due to minute irregularities in the alignment of the bearing parts. If for example, a tool is forced tightly against the work, particularly a mounted tool with a screw feed or the like, there is a tendency of the parts forming the cylinder member to buckle to an almost infinitesimal degree and yet sufficiently to throw the guiding means for the hammer extension out of line, resulting in a slight binding action on the hammer extension, with the result that the latter is scored.

The object of the present invention is to provide means for overcoming the difficulty and the structure herein disclosed has been found to materially eliminate the scoring action.

In the accompanying drawings:

Figure 1 is a longitudinal sectional view of the preferred embodiment of the invention.

Figure 2 is a detail sectional view of the head bushing and the bearing bushing therein.

Figure 3 is a rear elevation of the same.

Figure 4 is a cross sectional view on the line 4-4 of Figure 2.

The cylinder member of the tool may be of any well-known or desired construction. As shown, it comprises a barrel 5, into the front end of which is fitted a head bushing 6, having an outstanding flange 7 that is clamped between the barrel 5 and the usual chuck housing 8.

The bushing 6 has its rear end portion chambered, as shown at 9, and loosely fitted into said chamber is a bearing bushing 10. It will be understood that while in the drawings a material amount of space is shown around and at the ends of the bearing bushing 9, in actual practice, this does not amount

to more than a few thousandths of an inch. The piston head of the tool is shown at 11 and is provided with the usual hammer extension 12, which in this case has a snug sliding fit in the bearing bushing 10. At its front end it is slidably interfit with the chuck 12a, adapted to receive a tool. The rear end portion of such a tool is shown at 13.

The head bushing 6 is provided with an annular external groove 14 that has communication with the chamber 9 through a plurality of ports 15 and said groove 14 is also in communication with the front end of a piston chamber 16 by means of longitudinal channels 17 cut in the periphery of the head bushing 6 and extending from the channel 14 through the rear end of said bushing. In order to hold the bearing bushing 10 against detachment, it is provided with an annular groove 18 that loosely receives a retaining pin 19 carried transversely by the head bushing 6.

With this structure, it will of course be evident that the hammer extension 12 has a sliding bearing in the bearing bushing 10, and that the latter has a limited lateral and longitudinal movement in the head bushing. By allowing the motive fluid access to the space around the bushing 10, said bushing has in effect a floating movement due not only to the entrance of the fluid but to lubricant carried by said fluid. This, it is found material reduces the danger of the hammer extension being scored and resultantly obviates breakage of this part.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim, is:

1. In a fluid operated tool, the combination with a cylinder member and a reciprocating piston therein, of an element in which the piston has a reciprocating bearing, said ele-

ment having a limited lateral play to permit its lateral movement by reason of lateral pressure thereon of the piston.

2. In a fluid operated tool, the combination with a cylinder member and a reciprocatory piston therein, of a bushing in the cylinder member and in which the piston has a reciprocatory bearing, said bushing having limited lateral freedom of movement in the cylinder member to permit its lateral movement by reason of lateral pressure thereon of the piston.

3. In a fluid operated tool, the combination with a cylinder member having a piston chamber, of a reciprocatory piston in the chamber having a hammer extension, and a bushing in the cylinder member and in which the hammer extension has a reciprocatory bearing, said bushing having limited lateral freedom of movement to permit it to accommodate itself to any lateral pressure that is brought against it by the piston during its reciprocation.

4. In a fluid operated tool, the combination with a cylinder member having a piston chamber, of a reciprocatory piston in the chamber having a hammer extension, a bushing in the cylinder member and in which the hammer extension has a reciprocatory bearing, said bushing having limited lateral freedom of movement to permit it to accommodate itself to any lateral pressure that is brought against it by the piston during its reciprocation, and means for directing fluid under pressure around and against said bushing to cause it to have a "floating" action.

5. In a fluid operated tool, the combination with a cylinder member having a piston chamber, of a reciprocatory piston in the chamber having a hammer extension, a bushing in the cylinder member and in which the hammer extension has a reciprocatory bearing, said bushing having limited lateral freedom of movement to permit it to accommodate itself to any lateral pressure that is brought against it by the piston during its reciprocation, and a motive fluid passageway leading from the front end of the piston chamber and directing fluid under pressure around and against said bushing to cause it to have a "floating" action.

6. In a fluid operated tool, the combination with a cylinder member comprising a barrel having a piston chamber therein, of a head bushing for the front end of the barrel having an internal chamber, a bearing bushing having a loose fit in the internal chamber and capable of limited lateral play therein, and a piston in the piston chamber having a hammer extension, said extension having a sliding fit in the bearing bushing.

7. In a fluid operated tool, the combination with a cylinder member comprising a barrel having a piston chamber therein, of a head bushing for the front end of the barrel hav-

ing an internal chamber, a bearing bushing having a loose fit in the internal chamber and capable of limited play therein, a piston in the piston chamber having a hammer extension, said extension having a sliding fit in the bearing bushing, and a passageway for fluid under pressure leading from the front end of the piston chamber to the internal chamber outside the bearing bushing.

In testimony whereof I affix my signature. 75
ROBERT O. OLANDER.
